UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS FOR THE CONVERSION OF PETROLEUM OILS.

Application filed August 16, 1922, Serial No. 582,294. Renewed June 2, 1927.

This invention refers to improvements in a process and apparatus for the conversion of petroleum oils, and refers more particularly to a process in which relatively high boiling point oils are converted into oils having a low boiling point, or characteristics similar to gasoline and the like.

The invention refers particularly to a continuous process for treating oils under substantial pressure of the generated vapors, pressure being controlled by valves interposed in the various lines connecting the separate stages, and a pressure relief valve on the receiver.

15 The single figure is a diagrammatic side elevational view of the apparatus with parts in section.

Referring to the drawings, the oil to be treated is introduced from any convenient source through the line 1 and is charged by means of a pump 2 through the line 3 regulated by the valve 4. The charging line 3 is connected near the top of a dephlegmator or refluxing tower 5 so that the raw oil or incoming cool oil is introduced in the top thereof and acts as a cooling medium for the vapors which rise from the conversion stage through the dephlegmator. The oil with a considerable condensate content which comprises the high boiling point fractions separated from the oil vapors, collects in the bottom of the dephlegmator and drains down through the vapor line 6 against the travel of the oil vapors into the reacting or vaporizing chamber 7. In the center of the chamber 7 is positioned a partition wall 8 which serves to retard the movement of the oil during vaporization, giving it ample time to effect a relatively complete digestion and assume an equilibrium while being maintained in a substantial body in the vaporizing chamber.

In the bottom of the retort or chamber 7 are connected the headers 9 and 10 which have heating tubes 11 connected therebetween. The heating tubes and headers are mounted in a furnace 12 preferably heated by means of gas burner 13.

50 In operation, the oil is introduced as explained and after serving as a dephlegmating medium in the refluxing column, flows down with its condensate content into the vaporizing chamber 7. The partition wall 8 prevents the incoming oil from mixing with the heated vaporizing oil in the other portion of the chamber which is separated by

the partition. The oil thence flows down through the header 9, and after passing through the heating tubes 11, rises through the header 10 into the opposite end of the vaporizing chamber designated as 7a. In this portion of the chamber, a substantial part of the vaporization takes place, the free carbon and liquid residue being drawn off through line 14 controlled by the valve 15. The header 10 extends into the chamber 7a in the form of a standpipe to prevent the carbon from draining back into the lower portion of the header and becoming trapped in the heating zone. The vapors rising from the oil pass out through the vapor line 6 controlled by valve 70 16 against the travel of the incoming oil. After rising through the dephlegmator and being subjected to a refluxing action, the still vaporized portion passes off through the line 17, controlled by the valve 18 to the water 75 condenser coil 19 mounted in the condenser box 20, the distillate passing from the discharge end of the condenser coil through line 21 regulated by the valve 22, to the receiver 23.

The receiver is equipped with pressure relief valve 24, liquid drawoff valve 25, pressure gauge 26 and liquid level gauge 27.

By treating the oil in this manner the reflux condensate may be recycled both through the vaporizing and heating zones without producing any objectional cooling during the conversion reaction. Also, the heat of the system may be economically used in re-treating these high boiling point products which would otherwise have to be separately treated, or returned through means which would subject them to substantial cooling.

By treating Mid-Continent gas oil of approximately 30 to 32° Baumé gravity, to temperatures ranging from 600° to 900° F., and pressures from 50 to 350 pounds, a substantial yield of approximately 30% of the oil treated may be obtained, the distillate having a gravity of from 50° to 52° Baumé of Navy 100 specification gasoline, which requires an initial boiling point below 130° F. and an end boiling point at or below 437° F.

I claim as my invention:

1. A continuous process for cracking hydrocarbon oil, consisting in introducing charging oil in intimate contact with evolved vapors flowing through a dephlegmator, in taking off dephlegmated vapors from the dephlegmator for condensation and collecting

tion, in passing the charging oil, together with reflux condensate separated from the vapors, from said dephlegmator to an enlarged vaporizing zone, counter-current to the flow of the vapors from such enlarged zone to the dephlegmator, in maintaining the preheated charging oil and reflux condensate in a pool in said enlarged vaporizing zone, in passing preheated charging oil and reflux condensate from said pool through a heating zone wherein such substances are heated to a cracking temperature, in introducing these highly heated substances from the heating zone to an independent pool in said enlarged vaporizing zone from which independent pool heavy unvaporized residual oil is continuously withdrawn to be isolated from the system and from which no oil is returned to the heating zone and in maintaining a super-atmospheric pressure on the oil undergoing conversion.

2. A process for cracking hydrocarbon oils which comprises maintaining a bulk supply of oil in a supply zone, continuously passing oil from said supply zone through a heating element wherein it is raised to a cracking temperature, introducing the heated oil from said heating zone into a separating zone, in removing carbonaceous constituents from said separating zone, maintaining the oil constituents in said separating zone and the body of oil in said supply zone in indirect heat interchange relationship, uniting vapors evolved from the oil in said separating zone with vapors released from the oil in said supply zone, in subjecting such vapors in a commingled state to dephlegmation in a dephleg-

mating zone, in introducing fresh charging oil for the process to said dephlegmating zone to effect the condensation of the insufficiently cracked vapors in returning reflux condensate together with the fresh oil which has been introduced to said dephlegmating zone to said supply zone and in so controlling the liquid level in said supply zone that the oil constituents therein cannot overflow from said supply zone into said separating zone.

3. A process for cracking hydrocarbon oil which comprises maintaining a substantial body of oil in a supply zone, passing oil from said supply zone through a heating zone wherein it is raised to a cracking temperature, delivering the heated oil from said heating zone into a separating zone wherein a body of liquid oil collects, maintaining the liquid oil constituents in said separating zone in indirect heat interchange relationship with the body of oil in said supply zone, maintaining the oil constituents in said separating zone and the oil body in said supply zone in substantially the same horizontal plane, controlling the liquid level in said supply zone to prevent the overflow of oil from said supply zone into said separating zone, subjecting vapors evolved from the oil in said separating zone to reflux condensation in a reflux condensing zone, in introducing charging oil for the process to said reflux condensing zone to condense the insufficiently cracked vapors and introducing reflux condensate separated from the vapors and fresh charging oil which has been introduced to said reflux condensing zone to said supply zone.

GUSTAV EGLOFF.
